UNITED STATES PATENT OFFICE.

KARL FREDRIK OLSON, OF BROCKTON, MASSACHUSETTS.

PORTABLE FIRE-ESCAPE.

1,113,369.

Specification of Letters Patent.

Patented Oct. 13, 1914.

Application filed June 17, 1914. Serial No. 845,672.

To all whom it may concern:

Be it known that I, KARL FREDRIK OLSON, a citizen of the United States, residing at Brockton, in the county of Plymouth and State of Massachusetts, have invented certain new and useful Improvements in Portable Fire-Escapes, of which the following is a specification, reference being had to the accompanying drawings.

This invention relates to new and useful improvements in fire escapes, and particularly to that class of fire escapes which are portable.

An object of this invention is the provision of a fire escape which is relatively small in size so that the same may be easily carried about from place to place in a trunk or the like, the device being adapted for easy and rapid connection to the frame of a window so that a person using the same may quickly lower himself to the ground.

A further object of this invention is the provision of a fire escape which comprises a yoke having a pair of hooks connected thereto for supporting the device upon a window ledge or the like, the yoke carrying a block around which a rope is passed, one end of the rope carrying a body support, the free end of the rope being grasped by the person carried by the body support so that he may lower himself to the ground, the frictional engagement of the rope with the block materially relieving the weight of the body upon the arms of the person.

With these and other objects in view, my invention consists in the novel construction, combination, and arrangement of parts to be hereinafter more fully described, claimed, and illustrated in the accompanying drawings, in which,

Figure 1 is a perspective view of my device, showing the same in use; Fig. 2 is a perspective view of the body support; and Fig. 3 is a detail sectional view.

Referring more particularly to the drawing, the numeral 1 designates a U-shaped supporting plate, the parallel ends of which are provided with angular openings 2 through which extend the angular ends 3 of a cylindrical block 4. Connected to each projecting end 3 of the block is one end of a rod 5, the rods rearwardly of the plate being twisted as at 6, and being thence bent to form hooks 7 by means of which the device may be supported upon the ledge of a window or the like. A cord 8 is passed

around the block 4, one end of the cord being passed through an opening 9 in the plate intermediate of its ends, the end of the cord which extends through the opening being connected at its extremity to a body support. The body support comprises a chest encircling strap 11 which is provided at one end with a series of openings 12, the opposite end of the strap carrying a buckle 13, the tongue of the buckle being adapted to engage through any one of the openings 12 so that the chest strap may be secured around persons of various sizes. Secured to the strap 11 adjacent its opposite ends are the ends of a supporting strap 14 which is connected intermediate of its ends to the free end of the cord 8 after the same is passed through the opening 9 in the plate 1, the intermediate portion of the strap 14 being disposed over the head of the person who is carried by the chest strap 11.

In the practical use of my improved fire escape, the hooks 7 are engaged over the sill of a window or an article of furniture within the room from which it is desired to lower one's self, and the chest strap 11 is engaged around the body and secured thereto, whereupon the person grasps the end of the rope closely adjacent to the cylindrical block 4 and lowers himself by allowing the free end of the cord to pass upwardly so that the body support is lowered to the ground. It will be seen that the frictional engagement of the cord 8 around the block 4 acts as a brake upon the body support, so that less pressure is necessary upon the free end of the cord than the weight of the body carried in the support to hold the same from dropping quickly to the ground.

It will be seen that I have provided an extremely simple fire escape which may be cheaply manufactured, and which may be quickly applied to use, the escape being very light and compact in form so that the same may be readily carried about from place to place in a trunk or other similar traveling case.

It will be seen that the frictional engagement of the cord with the block 4 may be regulated by the number of times the cord is passed around the block, the greater number of coils around the block causing the greater amount of friction between the cord and the block so that less power is necessitated to hold the carrier from speedy descent.

Having thus fully described my invention, what I desire to claim and secure by Letters Patent, is:—

1. A device of the character described comprising a U-shaped supporting plate, the opposite ends of said plate having angular openings formed therein, a cylindrical block disposed between the opposite ends of said plate and having angular extensions disposed through the angular openings in said ends, hooks connected at one end to said angular extensions, a cord passed around said block, and a body carrier connected to one end of said cord.
- 15 2. A device of the character described comprising a plate having its opposite ends disposed angularly in parallel relation with each other, said plate having angular openings formed therein, a block having angular extensions disposed through said angular openings, hooks secured at one end to said angular extensions, said plate having a central opening, a cord passed around said block and having one end disposed through 25 the opening in said plate, and a body carrier connected to the free end of said cord after the same has been passed through the opening in the plate.
3. A device of the character described comprising a U-shaped supporting plate having

angular openings formed in its opposite ends, a block having angular extensions at its ends disposed through the angular openings in said plate, rods connected at one end to the angular extensions, said rods being twisted rearwardly of the plate and being curved to provide hooks, a cord passed around said block, and a body carrier connected to one end of said cord.

4. A device of the class described comprising a U-shaped plate having angular openings formed in its opposite ends, a cylindrical block having angular ends disposed through the openings in the ends of said plate, supporting hooks connected at one 45 end to the angular ends of said block, said plate having a central opening therein, a cord passed around said block, one end of said cord being disposed through the central opening of said plate, and a body carrier 50 connected to the free end of said cord after the same has been passed through the central opening in the plate.

In testimony whereof I hereunto affix my signature in the presence of two witnesses. 55

KARL FREDRIK OLSON.
